CLAIM

The ornamental design for a pressure vessel for curing plastic dentures, substantially as shown and described.

DESCRIPTION

FIG. 1 is an elevation view of a pressure vessel for curing plastic dentures showing our new design;

FIG. 2 is a top plan view thereof;

FIG. 3 is a bottom plan view thereof; and

FIG. 4 is a cross-section taken along line 4—4 of FIG. 2.

FIG. 1.FIG. 2.FIG. 4.FIG. 3.
